FLAT IRON SUPPORT AND HOLDER COMBINATION

Harold B. Avery, Philadelphia, Pa., assignor to I. R. Associates, Inc., New Orleans, La., a corporation of Louisiana

Filed Oct. 18, 1965, Ser. No. 87,534

Term of patent 14 years

(Cl. D49—6)

I claim:

The ornamental design for a flat iron support and holder combination, substantially as shown.
